(57) **CLAIM**

The ornamental design for a smart watch with health monitor sensor, as shown and described.

DESCRIPTION

FIG. 1 is a top, right side isometric view of our new design for a smart watch with health monitor sensor

FIG. 2 is a right side elevation view of FIG. 1.

FIG. 3 is a left side elevation view of FIG. 1.

FIG. 4 front side elevation view of FIG. 1.

FIG. 5 is a back side elevation view of FIG. 1.

FIG. 6 is a top plan view of FIG. 1.

FIG. 7 is a bottom plan view of FIG. 1.

FIG. 8 is a bottom, left side isometric view of FIG. 1.

FIG. 9 is a top, right side isometric view of our new design for a smart watch with health monitor sensor.

FIG. 10 is a right side elevation view of FIG. 9.

FIG. 11 is a left side elevation view of FIG. 9.

FIG. 12 front side elevation view of FIG. 9.

FIG. 13 is a back side elevation view of FIG. 9.

FIG. 14 is a top plan view of FIG. 9.

FIG. 15 is a bottom plan view of FIG. 9; and,

FIG. 16 is a bottom, left side isometric view of FIG. 9.

The features shown in broken lines in the drawings depict portions of the smart watch with health monitor sensor and form no part of the claimed design.
